Nº 3105

Thomas Dolan-Design for a Stocking Fabric.

PATENTED
JUL 14 1868

Charles Salmon
R. Williams

Thomas Dolan

United States Patent Office.

THOMAS DOLAN, OF PHILADELPHIA, PENNSYLVANIA.

Design No. 3,105, dated July 14, 1868.

DESIGN FOR A STOCKING-FABRIC.

The Schedule referred to in these Letters Patent and making part of the same.

TO ALL WHOM IT MAY CONCERN:

Be it known that I, THOMAS DOLAN, of the city and county of Philadelphia, State of Pennsylvania, have invented or produced a new and original Design for a Stocking-Fabric; and I do hereby declare that the accompanying drawing, and the following explanation thereof, form a full, clear, and exact description of the said design.

The figure in the drawing represents sufficient of the knitted fabric to illustrate the design.

In the body A of the fabric are parallel rows of diamond-shaped spots *a*, and on each side of each row is a similar row of diamond-shaped spots *b*, arranged, in respect to the spots of the central row, as clearly illustrated in the drawing.

The spots *a* should differ in color or shade from the spots *b*, and both should differ in color or shade from the body of the fabric.

Without confining myself to any specific color or shade—

I claim the design for a stocking-fabric, substantially as herein described, and represented in and by the accompanying drawing.

In testimony whereof, I have signed my name to this specification in the presence of two subscribing witnesses.

THOMAS DOLAN.
